UNITED STATES PATENT OFFICE

RALPH H. MCKEE, OF NEW YORK, N. Y., AND EARLE H. MORSE, OF NUTLEY, NEW JERSEY, ASSIGNEES TO ALEXANDER HERZ, OF NEW ROCHELLE, NEW YORK

DEPILATORY AND METHOD OF COMPOUNDING THE SAME

No Drawing.

Application filed January 4, 1932. Serial No. 584,758.

This invention relates to a new and improved depilatory compound for removing hair from the human body and to the process of preparing the same.

5 The primary object of the present invention is to provide a depilatory compound which is effective and rapid in its action, relatively stable over long periods, non-toxic and non-irritating when applied to the human skin, and particularly adapted for preparation as an attractive toilet article.

10 During recent years, the recognition, particularly by members of the feminine sex, of depilatory compounds as almost indispensable toilet preparations has become increasingly widespread. As a result of this increased use of depilatories, and especially because of the exacting requirements of the feminine sex with respect to toilet preparations, the standard of quality demanded of depilatory compounds has been raised to a materially higher level than has been attained by depilatory compounds heretofore available.

15 In order to satisfy present day requirements, a depilatory compound should have the following characteristics: It should be effective and rapid in its action; it should be relatively stable on exposure to air; it should be non-toxic and substantially non-irritating when applied to the human skin; it should be light in color and preferably pure white; and it should be odorless or at least susceptible to effective perfuming.

20 The depilatory compounds which heretofore have generally been employed for the purpose described fail by a considerable margin to meet the requirements outlined above. The most commonly used depilatories invariably employ a sulfur compound, such as an alkali sulfid, as the active depilating agent with the result that such depilatories have an exceedingly disagreeable and nauseating odor which it is impossible to overcome despite the many attempts that have been made to mask it by the addition of perfumes and deodorants. For this reason the sulfur-containing depilatories are highly objectionable as toilet preparations. Moreover, they are otherwise objectionable, when

considered as articles for the toilet, on account of their color which generally ranges from a dull blue to a dark gray. In addition, they are readily decomposed and are rendered partially or wholly ineffective by exposure to air and are therefore required to be kept thoroughly sealed from the atmosphere to prevent deterioration. Finally, some of the sulfur-compounds employed are active poisons and cannot be used freely on the human skin, particularly about the lips, without producing ill or unpleasant effects.

25 We are aware that depilating agents which will not possess the disagreeable characteristics of the sulfur-containing agents when used in depilatory compounds has been proposed, and that thallium salts have been used for this purpose. However, thallium salts are objectionable in that they are poisonous and also because they do not act primarily upon the hair but rather upon the nerves or blood vessels surrounding the roots of the hair whereby after several applications the individual hairs become loosened from their follicles and may be pulled out. Consequently, a thallium salt compound of this nature which enters the system and becomes effective only by operating as a drug upon the roots of the hair is not a depilatory in the sense in which the term is generally understood and in which we use it herein.

30 We have discovered that the above referred to objections and disadvantages which have heretofore attended depilatory compounds can successfully be overcome, and have produced a depilatory compound which possesses all of the characteristics of a completely satisfactory depilatory as set forth above.

35 In its fundamental aspect, the theory of our invention is based on the disintegrating effect of divalent tin in alkaline solution on the keratin molecule of the hair, and more particularly on the reducing action of divalent tin in alkaline solution on the cystine group of the keratin molecule to form cysteine, the alkali salts of which are water soluble. In order that this property of divalent tin may be advantageously utilized in connection with the removal of hair from the human body, we employ as the active depilat-

ing agent in our new preparation a relatively soluble stannite, preferably an alkali stannite such as sodium stannite, and combine it with other ingredients to render the preparation stable and impart to it a substantial rapidity of action upon the hair without producing an irritating effect upon the surface of the skin.

The employment of a relatively soluble stannite as an active depilating agent results in advantages which are not obtained by the use of other divalent tin compounds. For example, insoluble divalent tin compounds, such as some of the stannous salts, are not suitable since they cannot be brought into effective contact with the hair. Moreover, stannous chloride, which is the most common divalent tin salt and is quite readily soluble in water, is not suitable for use by itself since it does not attack the hair. However, when combined with an alkali-forming metal hydroxid the stannite thus produced will possess a disintegrating effect upon the hair, the rate of the disintegration being primarily dependent upon the degree of solubility of the particular stannite formed. For example, the nearly insoluble calcium stannite, which would be formed by combining stannous chloride with calcium hydroxid, will act upon the hair, but the action is much too slow to be of practical use as a depilating agent of the type here referred to. The speed of destruction of the hair by a depilating agent of the character described depends upon the time required for such agent to penetrate the hair in substantial concentration. While the speed of action may be increased to some extent by increasing the alkalinity of the depilating mixture, the limits to which such alkalinity may go without rendering the mixture too caustic and irritant to the human skin are low.

In order to provide a depilating mixture which will be relatively rapid in its action without being excessively alkaline, we employ as the active depilating agent a relatively soluble stannite, and preferably one that is considerably more soluble than calcium stannite. As stated above, our preference is for an alkali stannite and especially sodium stannite though other stannites more soluble than calcium stannite, such as barium stannite, work well. In some cases a mixture, such as a mixture of barium stannite and a small amount of sodium stannite, is particularly effective as it is rapid in action but not irritating to the skin.

A buffer action to control the alkalinity may be obtained by the addition of any amphoteric metal in a form in which reaction will readily take place with excess caustic alkali and such will permit the addition of substantial proportions of strong alkali, if desired, without having free caustic alkali present in the mixture in sufficient amount

to attack the skin surfaces during the time required to destroy the hair structure. The amphoteric metals commonly available are tin, zinc and aluminum. Tests show that these are satisfactory for imparting a buffer action in the present invention but our preference is for tin. In the event that tin alone is employed as a buffer, it is preferably used in the form of stannous hydroxid.

In order to facilitate the penetration of the active depilating agent into the hair structure we prefer to include in the depilatory mixture a suitable wetting agent, i. e. a surface tension reducing agent. Various known wetting agents may be employed, as will be apparent, but we prefer to use a pure soap, such as sodium oleate. Such material not only serves as an advantageous wetting agent and softener for the hair but it also has an emollient and soothing action on the skin and serves to prevent the other constituents present in the mixture from producing irritation.

In preparing our depilatory mixture in the form of an attractive toilet article we increase the consistency of the preparation by adding an inert filler in an amount sufficient to provide a cream or paste having the consistency of tooth paste or soft shaving soap. Various inert fillers may be employed and among those which are most suitable may be mentioned natural white clays, white diatomaceous earth, and silicates of alkaline earth metals, such as magnesium silicate which is white in color and inexpensive. These fillers also seem to have the property of acting as buffers to reduce any caustic effect of the compound on the skin.

In the preferred practice of compounding our depilatory preparation, we form sodium stannite by reacting stabilized stannous hydroxid with sodium hydroxid. While sodium stannite obviously may be derived by mixing stannous chlorid, which is the common source of stannous compounds, with caustic soda, this is disadvantageous in the practice of the present invention since brown hydrated stannic oxid and gray metallic tin are ordinarily formed in addition to the normal sodium stannite, and both of the former will impart an undesirable dark color to the compound. Moreover, the normal sodium stannite which is produced as a result of this reaction is relatively unstable. Consequently, we prefer to first prepare stannous hydroxid and then stabilize this compound with an alkali salt of a polybasic organic acid, such as the hydroxy acids, tauric or citric acid. The resulting stabilized stannous hydroxid is then reacted with sodium hydroxid solution which is then mixed with the other ingredients as suggested above and in the manner hereinatfer described in detail.

The following specific example of the preferred method of compounding our new depilatory compound as an attractive toilet article may be considered as illustrative of 5 the invention:

Stannous hydroxid is prepared by dissolving 100 g. of "tin salt" ($\text{SnCl}_2 \cdot 2\text{H}_2\text{O}$) in 400 cc. of water, and slowly adding this solution to a solution of 60 g. of commercial soda 10 ash (dry sodium carbonate) in 1000 cc. of water. Just prior to the addition of the stannous chlorid solution to the soda ash solution, the former is diluted with an additional 400 cc. of water. The stannous hydroxid separates as a white gelatinous precipitate which settles rapidly. This precipitate 15 is washed by decantation five or six times and finally allowed to settle, after which the excess liquid is drawn off from above the precipitate. The foregoing reaction is preferably conducted at about ordinary room temperature.

In order to stabilize the stannous hydroxid the precipitate formed as above is mixed with 25 46 g. of sodium potassium tartrate (Rochelle salts) dissolved in a small amount of water. The stabilizing action which results from this treatment is probably similar to that of Rochelle salts on cupric oxid in Fehling's 30 solution, that is, it is apparently due to the formation of complex tartaric acid salts stable in solutions of modified alkalinity. The volume of the precipitate formed as a result of the above described treatment is about 400 cc. and it contains roughly about 56 g. SnO . It is a mass of about the consistency of thick cream. In the final mixture which constitutes the depilatory, a sufficient quantity of this liquid mass is used to give approximately 40 a 3.5 per cent. SnO content to the mixture.

We next prepare a 20 per cent. caustic soda solution in an amount containing about two mols sodium hydroxid for each atom of tin to be treated in the next step.

45 The two liquid masses thus prepared are mixed together in order to produce the desired soluble sodium stannite. Only about half of the stannous hydroxid dissolves in this amount of alkali; the balance acting as 50 a buffer to control the alkalinity. The soluble sodium stannite resulting from this reaction is not the normal unstable sodium stannite but is apparently a more stable form of stannite. It is completely stable, any 55 tendency toward decomposition having been checked by the addition of the Rochelle salts to the compound, and its effective depilatory action will remain unimpaired in the compound for any length of time provided the 60 compound is not given a long exposure to direct sunlight.

To the thus prepared product are added 10 g. of sodium oleate (powdered white soap) and thoroughly incorporated therewith by stirring. This addition of sodium

oleate converts the creamy liquid into a thin white paste. Instead of adding sodium oleate as the first step of making a paste, the liquid carrying stannous hydroxid in suspension or even the filtrate from the suspended matter may, with proper dilution, be used as a liquid depilatory. 70

The relatively thin paste resulting from the preceding treatment with sodium oleate is thickened by the addition of an inert filler 75 of the type referred to above in order to provide a soft cream or paste which may be readily dispensed from a collapsible tube. The consistency of the paste may also be modified by the addition of glycerine or other 80 emollients.

A depilatory thus prepared will be white, odorless, substantially non-irritating, non-toxic, stable except upon long exposure to sunlight, and extremely rapid in its action upon the hair, destroying the structure of the hair rather than completely dissolving it but enabling the hair, a few minutes after application, to be completely removed by a slight rubbing action on the skin. Having 85 the above characteristics, the improved compound may be dispensed as an attractive toilet cream.

In using the term odorless in the appended claims, we refer to a compound embodying the invention described above and therefore intend to include all such compounds whether with or without an added perfuming agent. By the expression for use in removing hair from the human body we refer particularly 90 to the property of our improved compound of rapidly acting upon the hair without producing any substantial irritating effect on the skin, for to be practicable for such a purpose as is referred to, a compound must 95 act mildly on the skin and yet effectively upon the hair in a very few minutes. However, we do not wish it to be understood that the appended claims are thereby limited to compounds whose action is more rapid than the 100 use specified reasonably requires.

We claim:

1. A depilatory compound for use in rapidly removing hair from the human body and containing as an active depilating agent 115 a relatively concentrated alkaline solution of a stannite more soluble than calcium stannite, and a stabilizing agent for said stannite.

2. A depilatory compound for use in rapidly removing hair from the human body and containing as an active depilating agent a relatively concentrated alkaline solution of a stannite more soluble than calcium stannite, and a stabilizing agent for said stannite comprising an alkali salt of a polybasic hydroxy 120 organic acid.

3. A depilatory compound for use in rapidly removing hair from the human body and containing as an active depilating agent 125 a relatively concentrated alkaline solution of a

a stannite more soluble than calcium stannite, and a stabilizing agent for said stannite comprising Rochelle salts.

4. A depilatory compound for use in rapidly removing hair from the human body and containing a soluble stannite as an active depilating agent, an excess of free caustic alkali, and an amphoteric metal in a form in which reaction will rapidly take place with

10 said free caustic alkali.

5. A depilatory compound for use in rapidly removing hair from the human body containing a soluble stannite as an active depilating agent, an excess of free caustic alkali, and stannous hydroxid.

15 6. A depilatory compound for use in removing hair from the human body which contains as an active depilating agent a soluble stannite of a concentration of approximately 20 3.5 per cent calculated as SnO.

25 7. In a process of compounding a white depilatory containing a stannite more soluble than calcium stannite and for use in removing hair from the human body, the steps of preparing the stannite which comprise preparing stannous hydroxid by reacting stannous chlorid with an alkaline salt and combining the resulting stannous hydroxid with an alkali, and adding a buffer to control the 30 alkalinity of the compound.

35 8. In a process of compounding a white depilatory containing a stannite more soluble than calcium stannite and for use in removing hair from the human body, the steps of preparing the stannite which comprise preparing stannous hydroxid by reacting stannous chlorid with an alkaline salt, washing and then stabilizing the resulting stannous hydroxid, and finally combining the 40 stannous hydroxid with an alkali.

In testimony whereof, we have signed our names to this specification this 31st day of December, 1931.
